REEL

Fritz Dotsch, White Plains, N. Y.

Application January 29, 1947, Serial No. 725,092

5 Claims. (Cl. 242—105)

1

This invention relates to a device in the nature of a holder or reel for material, such as steel tape or cable, when coiled, and which enables the material to be coiled or wound in the device and to be wholly or partly uncoiled or unwound from the device for use.

An object of the invention is the provision of a device of the indicated character which obviates the use of a drum or the like and the operating means therefor, yet enabling steel tape and analogous material to be wound and unwound with only slight manual effort.

A further object of the invention is the provision of improvements in a device of the character mentioned, whereby to compensate for the increase or decrease in the diameter of the outer convolution of the wound or coiled material as it is either being wound or unwound, and to insure the starting of the material upon its circular course as the winding operation is begun.

The invention also resides in the simplicity of a device of the indicated character, the economy with which it may be produced, and the general benefits derived therefrom.

The nature of the invention and its distinguishing features and advantages will appear when the following specification is read in conjunction with the accompanying drawing, in which—

Fig. 1 is a side view of one embodiment of the present invention, showing a coiled headed steel tape or "snake" by way of example, a portion of the tape being shown unwound in dotted lines.

Fig. 2 is a sectional view taken on the line 2—2 of Fig. 1.

Fig. 3 is an enlarged fragmentary sectional view taken on the line 3—3 of Fig. 1.

Fig. 4 is a sectional view taken on the line 4—4 of Fig. 3.

Fig. 5 is an enlarged fragmentary sectional view taken on the line 5—5 of Fig. 1.

Fig. 6 is a side view of a device embodying modifications according to the present invention, a portion being broken away to show certain features.

Referring now more particularly to the drawing, it will be apparent that the device includes a frame 10 composed of pieces or lengths of metal or other suitable material. In the present instance two pieces of metal are used and each is bent into U-shape providing side members 11 joined by an end portion 12, said pieces being further bent to provide overlapping terminals secured by a suitable fastener 13 to provide the opposite end portion 14. The pieces thus bent and secured are

2

arranged to intersect each other and a screw bolt 15 extends through the pieces. Nuts 16 on the bolt 15 together with the end portions 12 and 14 maintain the side members 11 spaced in parallel side by side relation. Thus, the frame 10 comprises pairs of side members 11 which extend radially with respect to an axis provided by the bolt 15.

Rollers are arranged between the side members 11, there being one roller 17 between the members 11 of each of two pairs with the arbor 18 of the roller supported by the respective members 11, and there being one roller 19 whose arbor 20 is supported by a slide 21 at one end of the slide. There is one slide 21 engaged with the members 11 of each of two pairs for radial inward and outward movement. Each slide 21 is of generally U-shape and channel formation. A helical spring 22 has one end connected with each slide 21, as at 23, and its opposite end connected with the bolt 15, as at 24. The springs 22 constitute resilient means which constantly exert a pull on the slides 21 causing the rollers 19 to move radially inward and allowing them 25 to move radially outward with respect to the rollers 17 to cooperate with the latter and the members 11 in the material winding and unwinding operations. The springs 22 have a tension determined by the flexibility or resilience and 30 the thickness or the cross sectional size of the material to be wound and unwound.

The radial inward movement of each roller 19 is limited by suitable means, such as the crimps 25, in the respective members 11, which 35 crimps 25 serve as stops engaged by the slide 21.

As shown most clearly in Fig. 1, a rigid bar 26 has its opposite ends secured in any suitable manner to the end portions 14 of two pairs of the frame members 11. This bar 26 serves as a brace to maintain the radial relation of the members 11, serves as a handle, and also serves 40 as a means for guiding the material in its circular course as the winding operation is begun since the tail end of the material is kept from 45 springing outwardly beyond certain limits.

In order that the device may rest on a suitable support while winding the material, suitable feet 27 are detachably connected with two end portions 12 and 14 respectively, as shown.

By way of example, a headed steel tape or "snake" 28 is shown wound or coiled in the device. To wind or coil the tape the tail end is grasped with one hand while the device is held with the other hand. The tape is pushed into 55 contact with the periphery or the upper roller

17 adjacent the bar 26. The end of the tape is then guided into contact with the periphery of the lower roller 17, then into contact with the peripheries of the other lower and upper rollers 19 in the order named. This forms the first or innermost convolution. Then by further imparting a rotatory movement to the tape, it will be coiled or wound one convolution on another until the tape or "snake" is fully coiled as shown in Fig. 1. The members 11 limit or prevent lateral movement of the convolutions.

The "snake" may be fully uncoiled from the device for use in cleaning out sewer pipes or the like. Also, the "snake" may be partly uncoiled, and the device used by grasping the bar 26 and the coiled portion of the "snake" to rotate the uncoiled portion in carrying out a pipe or other cleaning or obstruction removing operation.

As shown in Fig. 6, the frame 10 may be cast in one piece to obviate the use of the bar 26. Also, auxiliary means in the form of longitudinally bowed members 29 may be used to cooperate with the rollers in the material winding and unwinding operations. One member 29 is secured to frame 10 adjacent one of the rollers 17 and another member 29 is secured to one of the slides 21 so as to be radially movable with the roller 19 carried by the slide. Each member 29 makes a two point contact with the outermost convolution of the wound material and limits or prevents outward flexure. This is desirable when thin tape is to be wound and unwound, and a large amount is wound forming a large coil. In other respects the device shown in Fig. 6 is like that shown in Figs. 1 to 5 and similar reference numerals are applied to corresponding parts.

It is to be understood the invention is not restricted to the details above described, but includes all constructions and modifications coming within the scope of the appended claims.

I claim:

1. A device of the character described comprising a frame, an arrangement of rollers, certain of said rollers having arbors supported by the frame and the remaining rollers having arbors on spring actuated slides respectively radially movable with respect to the frame so that the rollers on the slides are in cooperative diametrically opposed relation to said frame rollers, the provision and arrangement being such that a length of strip material may be coiled within the frame and uncoiled therefrom supported by the rollers with the outermost convolution of the coiled material contacting the rollers while the frame limits lateral movement of the convolutions.

2. A device as set forth in claim 1, and means on the frame for guiding the leading end of the material from one roller to another in starting the winding operation.

3. A device of the character described comprising radial pairs of frame members rigidly connected together, the frame members of each pair

being spaced in side by side relation, rollers, there being one roller arranged between the frame members of each pair, certain rollers having arbors supported by their related frame members, the remaining rollers having arbors supported by slides movable along their related frame members, and yieldable means connected with the slides and the related frame members to constantly urge the rollers carried by the slides radially inward toward the rollers supported by the frame members, the provision and arrangement being such that a length of strip material may be coiled in the device and uncoiled therefrom supported by the rollers with the outermost convolution of the coiled material contacting the rollers while the frame members limit or prevent lateral movement of the convolutions.

4. A device comprising a frame, rollers carried by the frame and disposed radially outward with respect to the transverse axis of the frame, slides engaged with the frame and movable radially with respect to said axis, rollers carried by said slides respectively, and resilient means connected with the frame and slides constantly acting to pull the rollers of the slides radially inward with respect to the rollers of the frame, for the purpose of winding and unwinding flexible material and for holding the material when wound, and auxiliary means carried by the frame and one of the slides adapted to restrain the outward flexure of the outermost convolution of the wound material.

5. A device comprising a frame, rollers carried by the frame and disposed radially outward with respect to the transverse axis of the frame, slides engaged with the frame and moving radially with respect to said axis, rollers carried by said slides respectively, and resilient means connected with the frame and slides constantly acting to pull the rollers of the slides radially inward with respect to the rollers of the frame, for the purpose of winding and unwinding flexible material and for holding the material when wound, and auxiliary members carried by the frame and one of the slides adapted to make a two point contact with the outer convolution of the wound material to restrain the outer flexure thereof.
